LOOM REPLENISHING MECHANISM

William R. Hewton, Philadelphia, Pa., assignor
to Collins & Aikman Corporation, Philadelphia,
Pa., a corporation of Delaware

Application March 1, 1939, Serial No. 259,080

11 Claims. (Cl. 139—242)

This invention relates to automatic weft replenishing looms provided with a supply of full or partially full bobbins, and a transerrer means for engaging a bobbin of the supply to insert it in a shuttle positioned in a compartment of a shuttle box and simultaneously eject the substantially exhausted bobbin carried by the shuttle.

More particularly, this invention is directed to an actuating mechanism for the transerrer means. This improvement avoids the necessity of providing a lower or special shuttle box construction for automatic bobbin replenishing double shuttle looms, and provides a mechanism which will insure a rapid ingress and egress of the bobbin engaging portion of the transerrer means from the shuttle compartments of the shuttle box.

Difficulty has been experienced in properly controlling the motion of the transerrer means on weft replenishing looms having a long replenishing stroke, or a long replenishing stroke and a short replenishing stroke, selectively or successively controlled as illustrated in United States patent to Bird and Hewton No. 2,136,331, of which I am one of the joint inventors.

This invention contemplates within its scope an attachment for present day pile fabric looms, which has a complete cycle for each pair of weft inserted. The pairs of wefts may be inserted simultaneously by shuttles thrown through superposed sheds from opposite sides of the loom.

According to a preferred embodiment of my invention, I mount on the crank shaft in vertical alignment with the picking balls an open face cam which cooperates with a follower roller, such as a ball bearing roller, rotatably mounted between the bifurcated arms of a pivoted spring pressed member. A special journal and guide device supports and directs a ram element pivoted to the spring pressed member. This construction affords substantially straight line movement of the ram and causes the downward thrust of the cam on the roller to be dissipated against a fixed stud shaft, thus affording long wearing life to the guide. The ram element supports a dagger engaging stud or studs for moving a replenishing dagger after the dagger has been set and retained in set position by a latch member, similarly to the manner disclosed in the aforesaid patent.

A vented tubular telescopic spring assembly prevents the follower from leaving the rapidly rotating and sharply inclined cam face and by building up air pressure aids in insuring that the transerrer means is free to move clear of the

path of the shuttle boxes after the completion of the long stroke of the transerrer means. The replenishing cycle may be initiated by a timing mechanism, weft fork, feeler mechanism, or the like.

An object of this invention is to provide a long wearing and direct acting actuator for the transerrer means of a replenishing loom.

A further object of this invention is to provide a replenishing actuator to cooperate with double shuttle loom shuttle boxes of conventional height.

Another object is to provide a replenishing actuator capable of effecting replenishment after each crossing of a shuttle.

Another object is to provide an actuator which is increasing in speed as the lay is approaching front center and its forward rate of movement is decreasing.

Another object is to provide means in addition to the follower spring to aid the spring in preventing overthrow of the follower from the cam.

Another object is to provide a transerrer actuator which will insure a rapid ingress and egress of the transerrer into and out of shuttle box on long replenishing strokes.

Further objects and advantages of this invention will be manifest from the detailed description of the attached drawing, wherein:

Figure I is a side elevation of double shuttle loom with certain parts omitted to more clearly show the location of the present improvement.

Figure II is a sectional view through line A—A of Figure I, showing the construction of the pivoted guide for the ram and the spring and telescopic assembly.

Figure III is a partial detail view of the spring and vented telescopic assembly.

Referring first more particularly to Figure I of the drawing, a frame 10 has appropriately journalled thereon crank shaft 11 and a lower main shaft 12, which may be driven from any suitable source of power in a known manner. The lay swords 13 are mounted on a sword shaft 14 and oscillate therewith. Sword shaft 14 is journalled in the frame. Intermeshing gears 15 and 16 are fixed on the shafts 11 and 12 respectively, and actuate the lay beam 17 through pitmans 18, which are pivotally connected to the swords 13. In general, the picking mechanism is the same on both sides of the loom, with treadle arm 19 adjustably supporting picking shoe 20, cooperating with double arm lever 21 through balls 22 to effect cross picking.

The bobbin magazine 23 mounted on a fixed

portion of the loom, such as the knife rail 24, has journalled thereon shaft 25 with a spring return (not shown) and a loosely mounted transerrer member 26, to the upper end of which the transerrer head 27 is pivotally and yieldingly journalled. The lower arm 28 of the transerrer member is yieldingly connected to the upper arm through compression spring 29, of ample initial strength to effect replenishment in a known manner.

Transfer dagger 30 is pivoted as at 31 to the lower arm 28, and is normally held up against the under side of knife rail 24 by torsion spring 32, one end of which is fastened in lower arm 28 and the other end of which presses down on extension 33 of the dagger 30.

Hook 34, pivotally held by stud 35 of a stationary bracket (not shown) fixed to the under side of the knife rail 24, serves to hold either tooth of the latch 36, so that the dagger 30 is held in position to engage one or the other of bunters 37, 38. The hook is released by bunter stud 39 on lay beam 17, which allows latch member 36 to reset in a manner similar to the detailed description in United States Letters Patent No. 2,136,331. Offset 40 on the lower end of latch 36 engages the dagger 30.

Shuttle box 41 on the replenishing side has two vertically aligned compartments, either of which may retain a shuttle 42 or 43. A bobbin 44 from the supply may pass through the upper compartment to refill a shuttle in the lower compartment. In the illustrated embodiment only one shuttle would be in a box at one time. The picker stick is represented at 45.

Cam 46, fixed to crank shaft 11, is continually in operative engagement with roller 47 by virtue of compression spring 48 and its assembly. Spring 48 surrounds telescoping tube members 49 and 50. An oil film separates the tube members and acts as a seal. Each of the tube members have inserted at one end, as by threads or a pressed fit end, pieces 51 and 52, recessed to provide a bearing for supporting studs 53 and 54. Stud 53 is fast to pivoted lever 55 and stud 54 is secured to stationary bracket 60. The end member 52 is vented as at 52'. This construction holds the spring 48 in horizontal position without material deflection or buckling, and the size of the vent is such that air pressure is built up within the telescoping members as the high point of the cam is reached. The air pressure aids the spring 48 in preventing overthrow of the follower roller 47 and gives an initial booster action to the rearward movement of pivoted lever 55 and roller 47, to effect return of roller 47 with the descending contour of the cam face, thus insuring smooth silent operation during normal weaving. On the stroke of the ram and cam, during which replenishment is effected, the bunters 37 and 38 will be quickly disengaged from the dagger 30. After disengagement, the return spring is free to function without restriction and the replenishing mechanism is reset for normal weaving.

Single face cam 46, as hereinbefore mentioned, makes a complete revolution for each crossing of the shuttle or shuttles. Its downward thrust on roller 47 is dissipated into the support stud 56 of the pivoted lever 55. Closed cams are not desirable because of their tendency to break, noise and initial cost, and cannot be used to produce the necessary length of stroke, as a closed cam of the required size would interfere with the

picking balls of conventional looms, over which the cam 46 is mounted.

Pivots connected to shaft 57 and between the bifurcated ends of lever 55 is a reciprocating ram 58, carrying on its forward upwardly extending end the dagger engaging bunters 37 and 38. This upwardly extending end is in the path of the lay but as it is always forwardly of the lay during weaving, direct actuation of the dagger 30 and transerrer is accomplished without resorting to an excessive linkage arrangement.

The ram 58 is guided in a channelled guide 59, pivotally mounted on bracket 60 secured to the loom frame 10, as by bolt 61. A pin key 62 extends into circular recess 63 to retain the channelled guide in place. The guide 59 automatically adjusts itself to the movement of lever 55 and aligns the bunters 37 and 38 with the dagger 30, which has been set after the call for replenishment.

Operation

The bunters 37 and 38 are reciprocated for each beat of the lay and forwardly thereof by the rotating cam on the crank shaft. The downward thrust of the cam on its follower is taken up in the fixed stud support and the follower is maintained on the cam face by its return spring, which together with the built up pressure in the telescoping members prevents overthrow of the follower from the cam face and insures quiet operation during normal weaving.

At substantial exhaustion of weft from a bobbin, replenishing is initiated as by a feeler and the latch is moved to engage one or the other of its teeth in the hook to align the dagger with the proper bunter to actuate the transerrer arm. The transerrer arm moves through the selected distance and against a fixed stop and inserts a bobbin from the supply. The spring and air pressure as in normal weaving keeps the follower on the cam so as to quickly release the dagger from the bunter, so that the transerrer may quickly withdraw without interference from the ram and cam motion.

Having described in a single embodiment my invention, but wishing to be restricted only to the scope of the following, I claim:

1. In a weft replenishing loom of the bobbin changing type having a forwardly and rearwardly moveable lay, a shuttle box mounted on the lay for movement therewith, a crank motion actuator including a crank shaft for the lay and the shuttle box and a transerrer arm on the transfer side of the loom; the combination of an actuator for the transerrer arm which includes a forwardly and rearwardly moveable ram member, a bunter on said ram member and means driven from the crank shaft which accelerates the forward motion of the ram member during the time the crank motion is decelerating the forward motion of the lay near the end of its travel in one direction.

2. In a weft replenishing loom of the bobbin changing type having a forwardly and rearwardly moveable lay, a shuttle box mounted on the lay for movement therewith, a crank motion actuator including a crank shaft for the lay and the shuttle box and a transerrer arm on the transfer side of the loom; the combination of an actuator for the transerrer arm which includes a forwardly and rearwardly moveable ram member, a bunter on said ram member and a cam on the crank shaft in operative engagement with

the ram member which accelerates the forward movement of the ram member during the time the crank motion is decelerating the forward movement of the lay near the end of its travel in one direction.

3. In a weft replenishing loom of the bobbin changing type having a forwardly and rearwardly moveable lay, a shuttle box mounted on the lay for movement therewith, a crank motion actuator for the lay and the shuttle box, a transerrer arm on the transfer side of the loom; the combination of a transerrer arm actuator which has a complete cycle of movement for each beat of the lay and which includes a forwardly and rearwardly moveable ram member, a bunter on said ram member, means for accelerating the forward motion of the ram member at the time the crank motion is decelerating the forward motion of the lay near the end of its travel in one direction and actuating means for imparting the forward and rearward movement to the transerrer arm actuator.

4. In a weft replenishing loom of the bobbin changing type having a forwardly and rearwardly moveable lay, a shuttle box mounted on the lay for movement therewith, a crank shaft actuator for the lay and shuttle box, a transerrer arm on the transfer side of the loom; the combination of a transerrer arm actuator which has a forward and rearward movement for each beat of the lay and which includes a ram member having an upstanding portion forwardly of the lay, a bunter on said upstanding portion, means for accelerating the forward motion of the ram member during the time the crank shaft is decelerating the forward motion of the lay near the end of its travel in one direction and actuating means for imparting the forward and rearward movement to the transerrer arm actuator.

5. In a weft replenishing loom of the bobbin changing type having a forwardly and rearwardly moveable lay, a shuttle box mounted on the lay for movement therewith, a crank shaft actuator for the lay and shuttle box, a transerrer arm on the transfer side of the loom; the combination of an actuator for the transerrer arm which includes a member pivoted on the loom frame, a cam follower on the pivoted member, a ram member pivotally joined to the pivoted member, a rotatable guide member in which the ram slides and a driving cam on the crank shaft which is in constant engagement with the cam follower and which accelerates the motion of the ram member during the time the crank shaft is decelerating the forward motion of the lay near the end of its travel in one direction.

6. In a weft replenishing loom of the bobbin changing type having a transerrer arm on the transfer side of the loom; the combination of an actuator for the transerrer arm which includes a reciprocating ram, a bunter on the ram, a cam follower operatively connected to the ram, a driving cam for the ram, means to keep the driving ram in operative engagement with the cam follower, said means comprising a spring operative at all times as well as means effective only at and shortly after front center to aid the spring when the reciprocating ram changes its direction of travel.

7. In a weft replenishing loom of a bobbin changing type having a crank shaft for driving the lay, a bobbin supply, a shuttle box, a shuttle in said box and a transerrer means for engaging a bobbin of the supply to transfer it into the shuttle; the combination of an actuator for the

transerrer means having an open face cam mounted on the crank shaft and rotatable therewith, a pivoted lever, a cam follower on said lever, a ram member pivoted to the pivoted lever, a rotatable guide for said ram and means for keeping the follower against the cam face.

8. In a double shuttle weft replenishing loom of the bobbin changing type having a forwardly and rearwardly moveable lay, a shuttle box mounted on the lay for movement therewith, a crank motion actuator for the lay and the shuttle box and a transerrer arm on the transfer side of the loom; the combination of a transerrer arm actuator which has a complete cycle for each beat of the lay and which includes a forwardly and rearwardly moveable ram member, a pair of bunters on said ram member and means for accelerating the forward motion of the ram member during the time the crank motion is decelerating the forward motion of the lay near the end of its travel in one direction.

9. In a double shuttle weft replenishing loom of the bobbin changing type having a forwardly and rearwardly moveable lay, a shuttle box mounted on the lay for movement therewith, a crank motion actuator including a crank shaft for the lay and shuttle box and a transerrer arm on the transfer side of the loom; the combination of a transerrer arm actuator which has a complete cycle of movement for each beat of the lay and which includes a forwardly and rearwardly moveable ram member, a pair of bunters on said ram members, a cam on the crank shaft for accelerating the forward motion of the ram member during the time the crank member is decelerating the forward motion of the lay near the end of its travel in one direction and a spring and vented telescoping assembly within the spring for keeping the ram and cam in operative relationship during weaving.

10. In a double shuttle weft replenishing loom of the bobbin changing type having a forwardly and rearwardly moveable lay, a shuttle box mounted on the lay for movement therewith, a crank motion actuator including a crank shaft for the lay and shuttle box, a transerrer arm on the transfer side of the loom; the combination of a transerrer arm actuator which has a complete cycle of movement for each beat of the lay and which includes a forwardly and rearwardly moveable ram member, a pair of bunters on said ram member, a cam on the crank shaft for accelerating the forward motion of the ram member during the time the crank motion is decelerating the forward motion of the lay near the end of its travel in one direction, said ram member being pivoted to a member pivoted on the loom frame and guided by a rotatable guide.

11. In a double shuttle weft replenishing loom of the bobbin changing type, having a forwardly and rearwardly moveable lay, a shuttle box mounted on the lay for movement therewith, a crank motion actuator for the lay and shuttle box, a transerrer arm on the transfer side of the loom; the combination of a transerrer arm actuator which has a complete cycle of movement for each beat of the lay and which includes a forwardly and rearwardly moveable ram member having an upstanding portion forwardly of the lay, a pair of bunters on said upstanding portion, and means for accelerating the forward motion of the ram member during the time the crank motion is decelerating the forward motion of the lay near the end of its travel in one direction.
